UNITED STATES PATENT OFFICE.

GEORGE L. SCHEEL, OF CHICAGO, ILLINOIS.

HAIR-DRYING DEVICE.

1,193,194.

Specification of Letters Patent.

Patented Aug. 1, 1916.

Application filed September 25, 1915. Serial No. 52,676.

To all whom it may concern:

Be it known that I, GEORGE L. SCHEEL, a citizen of the United States, and a resident of the city of Chicago, county of Cook, 5 and State of Illinois, have invented certain new and useful Improvements in Hair-Drying Devices, of which the following is a specification.

My invention relates to improvements in 10 hair drying devices and has for its object the production of a device of this character which will be of improved construction and efficient in operation.

Other objects will appear hereinafter.

The invention consists in the combinations 15 and arrangements of parts hereinafter described and claimed.

The invention will be best understood by reference to the accompanying drawings, 20 forming a part of this specification, and in which,

Figure 1 is a side elevation of a hair drying device embodying the invention, Fig. 2 is a top plan view thereof, Fig. 3 is a central vertical longitudinal section of the device, Figs. 4 and 5 are enlarged sections 25 taken on lines $x-x$ and $y-y$ respectively of Fig. 3, and Fig. 6 is a detail plan view of one of the insulating members employed 30 in the construction.

The preferred form of construction as illustrated in the drawings comprises a comb 1 from the back of which project spaced teeth 2. Formed in said comb back 25 is a longitudinally extending cylindrical chamber 3 and a longitudinally extending air passage 4 which preferably tapers or converges toward its forward end. Leading from the passage 4 to the teeth 2 are branch 30 passages 5 which converge or taper toward their outer ends. The branch passages 5 are formed as described in order to secure the greatest pressure upon the air discharged at the point of its emission, it 35 being clear that with this formation of the branch passages concentration toward the outer ends of said branch passages is effected with the result that a greater pressure upon the air will be secured at the 40 outer ends of said passages.

Coöperating with the comb is a handle 6 the front end 7 of which telescopes with the rearward end of the back of the comb as clearly shown in Fig. 3. Said parts are 45 held in operative relation by means of screws 8. Formed in the portion 7 in axial

alignment with chamber 3 and passage 4 are openings 9 and 10 respectively.

Arranged at the under side of the handle 6 is a compressible rubber bulb 11 one end 60 of which engages with a cap 12 secured by screws 12' to the rearward end of handle 6, an inwardly projecting nipple 13 secured to said cap engaging the opening provided in the adjacent end of said bulb. The opposite end of said bulb is held in operative position by means of a tube 14 which connects opening 10 with the passage 4 as shown, the rearward end of said tube projecting beyond the adjacent side of portion 70 7 for engagement in the opening in the front side of bulb 11. With this arrangement it will be seen that bulb 11 is detachably secured in position, detachment of the same being readily and easily effected by 75 disengaging the respective ends thereof from nipple 13 and tube 14. Coöperating with the nipple 13 is a check valve 15 of the flap valve type and provided in the forward end of tube 14 is a check valve 16 80 in the form of a disk adapted for slight movement in moving toward and from closing position. The tube 14 as will be seen is corrugated, and the corrugation provided in the forward end of said tube serves as a 85 seat for the valve 16 in the checking operation of the latter. The extreme forward end of tube 14 is longitudinally corrugated in order to allow for escape of the air around the valve 16 when the bulb 11 is 90 compressed. With this arrangement it will be seen that through successive compressions of the bulb 11 air will be pumped thereby into the passage 4 for discharge through the branch passages 5 as will be 95 readily understood.

Arranged in the tube 14 is a perfuming element 17 in the form of a piece of porous fibrous material which is saturated with any desired perfume. The member 17 is carried at the forward end of a resilient stem 18, the rearward end of the latter being bent back upon itself and formed for engagement with the corrugations at the adjacent end of tube 14 in order to releasably 100 hold said perfuming device in position 105 therein. With this arrangement it will be seen that air discharged from the bulb 11 will be perfumed in its passage through the tube 14. The perfuming element is located 110 in the discharge end of bulb 11 rather than at the entrance end thereof for the reason

that in the latter case it has been found that considerable of the perfume is wasted and spent before the same is discharged from the comb. With the arrangement disclosed it will be seen that the air is discharged practically immediately after being perfumed, thus preventing wasting of the perfume.

Arranged in the chamber 3 is a heating element in the form of a wire 19 of high electrical resistance which is wrapped upon a tubular core 20 of insulating material and preferably mica. Interposed between the wire 19 and the walls of chamber 3 is a second tube 21 of insulating material also preferably of mica. One of the terminals of the heating coil 19 is connected with one pole of a switch 22 which is mounted in a recess 23 formed in the upper side of handle 6 adjacent the front end thereof, a cover plate 24 secured to said handle by screws serving to securely hold said switch in position. The other terminal of said heating coil is connected through the medium of a screw 25 with one wire 26 of a pair of feed wires which lead to the device, the other feed wire 27 being connected with the other pole of the switch 22 as clearly shown in Fig. 3. With this arrangement it will be seen that the switch 22 controls the circuit of the heating element 19, making and breaking of said circuit being effected through depression of laterally projecting finger pieces 22' which project exteriorly through the opposite sides of the inclosing member 24. The feed wires 26 and 27 extend along the inner side of handle 6 which is grooved as at 28 in order to accommodate said wires. A sheet 29 of insulating material is interposed between said feed wires and the bulb 11 for the protection of the latter. The forward end of the member 21 is of channel form as shown at 30 in Figs. 3 and 6 in order to accommodate the adjacent terminal of heating coil 19, the opposite end of said insulating element being formed with a lip 31 which embraces an adjacent edge of handle 6 to securely hold said insulating member in operative position. A flexible housing 32 surrounds the feed wires 26 and 27 at their point of entrance to the handle 6 to prevent too sharp bending of the same as will be readily understood. With the construction set forth it will be seen that when heating coil 19 is energized through closing of the circuit therethrough, the back portion of the comb will become heated with the result of heating the air passing through the passage 4 and which is discharged through the branch passages 5. The effectiveness of the device as a hair drier is thus obviously increased.

In other hair drying devices which I have constructed as for example in the hair drier shown in my Patent #1,137,792, dated May

4th, 1915, I have mounted the control switch for the heating element of the device in the comb portion thereof. However I found through experiment that the heat generated by the heating element when in use was communicated to the switch, to the injury of the latter. In the present construction however it will be seen that I have corrected this defect in construction through mounting of the switch well within the handle of the device and therefore out of the zone of the heating element 19. The device is of durable and economical construction, of neat and finished design, and may be readily and easily manipulated by anyone.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. In a device of the class described, the combination of a comb comprising a back; teeth projecting from said back, there being a longitudinally extending air passage formed in said back having branch passages opening in the direction of said teeth; an electrically operated heating element mounted in said back; a handle connected with said comb; and a switch for controlling the circuit of said heating element mounted in said handle, substantially as described.

2. In a device of the class described, the combination of a comb comprising a back; teeth projecting from said back, there being a longitudinally extending air passage formed in said back having branch passages opening in the direction of said teeth; an electrically operated heating element mounted in said back; a handle connected with said comb at one end, there being a recess in said end of said back in which the adjacent end of said handle is fitted; and a switch for controlling the circuit of said heating element mounted in said handle, substantially as described.

3. In a device of the class described, the combination of a comb comprising a back; teeth projecting from said back, there being a longitudinally extending air passage formed in said back having branch passages opening in the direction of said teeth; a heating element mounted in said back; a handle connected with said comb at one end; a compressible bulb for forcing air through said passages; and means on said handle engaging with said bulb at opposite sides thereof for detachably holding the same in

operative position, substantially as described.

4. In a device of the class described, the combination of a comb comprising a back; 5 teeth projecting from said back, there being a longitudinally extending air passage formed in said back having branch passages opening in the direction of said teeth; a heating element mounted in said back; a handle connected with said comb at one end; a compressible bulb arranged at the under side of said handle, said handle being shaped to conform with the contour of the adjacent side of said bulb; and means on said handle 10 engaging with said bulb at opposite sides thereof for detachably holding the same in operative position, substantially as described.

5. In a device of the class described, the 20 combination of a comb comprising a back; teeth projecting from said back, there being a longitudinally extending air passage formed in said back having branch passages opening in the direction of said teeth; a heating element mounted in said back; a handle connected with said comb at one end; a compressible bulb arranged at the under side of said handle, said handle being shaped to conform with the contour of the adjacent 25 side of said bulb; and nipples on said handle detachably engaging with openings provided in opposite sides of said bulb for detachably holding the latter in operative position, substantially as described.

35 6. In a device of the class described, the combination of a comb comprising a back; teeth projecting from said back, there being a longitudinally extending air passage formed in said back having branch passages 40 opening in the direction of said teeth; means for forcing air through said passages; and a perfuming element interposed in said longitudinal passage, substantially as described.

7. In a device of the class described, the 45 combination of a comb comprising a back; teeth projecting from said back, there being a longitudinally extending air passage formed in said back having branch passages opening in the direction of said teeth; means 50 for forcing air through said passages; a perfuming element interposed in said longitudinal passage; and resilient means for holding said perfuming element in position in said passage, substantially as described.

8. In a device of the class described, the 60 combination of a comb comprising a back; teeth projecting from said back, there being a longitudinally extending air passage formed in said back having branch passages opening in the direction of said teeth; means for forcing air through said passages; a perfuming element interposed in said longitudinal passage, there being a recess in the 65 side of said passage; and resilient means en-

gaging with said recess for holding said perfuming element in position in said passage, substantially as described.

9. In a device of the class described, the combination of a comb comprising a back; 70 teeth projecting from said back, there being a longitudinally extending air passage formed in said back having branch passages opening in the direction of said teeth; means for forcing air through said passages; a corrugated tube inserted into said longitudinal passage; a perfuming element arranged in said tube; and resilient means adapted for releasable engagement with the corrugations of said tube for holding said 80 element in position in said passage, substantially as described.

10. In a device of the class described, the combination of a comb comprising a back; teeth projecting from said back, there being 85 a longitudinally extending air passage formed in said back having branch passages opening in the direction of said teeth; means for forcing air through said passages; a corrugated tube inserted into said longitudinal passage; a perfuming element arranged in said tube; resilient means adapted for releasable engagement with the corrugations at one end of said tube for holding said perfuming element in position in said passage; 90 and a check valve arranged in said tube coöperating with the corrugations in the opposite ends thereof, substantially as described.

11. In a device of the class described, the 100 combination of a comb comprising a back; teeth projecting from said back, there being a longitudinally extending passage formed in said back having branch passages opening in the direction of said teeth said branch 105 passages converging toward their outer ends, substantially as described.

12. In a device of the class described a comb comprising a back having an air passage and a chamber formed therein; teeth on said back, there being branch passages leading from said air passage opening in the direction of said teeth; an electrical heating element mounted in said chamber, 110 said heating element comprising a tubular core of insulating material; a conductor of high electrical resistance wrapped on said core; and a tube of insulating material interposed between said conductor and the walls of said chamber, substantially as described.

13. In a device of the class described, the combination of a comb comprising a back; teeth projecting from said back, there being a longitudinally extending air passage 115 formed in said back having branch passages opening in the direction of said teeth; an electrically operated heating element mounted in said back; a handle connected with said comb; a switch for controlling the 120 125 130

circuit of said heating element mounted in said handle; electrical feed wires coöperating with said heating element, said feed wires entering said handle in the rearward end thereof; and a groove provided in the inner side of said handle for the reception of said feed wires, substantially as described.

In testimony whereof I have signed my name to this specification in the presence of two subscribing witnesses.

GEORGE L. SCHEEL.
